UNITED STATES PATENT OFFICE.

GEORGE P. SHARP, OF CHICAGO, ILLINOIS, ASSIGNOR TO SHARP & SMITH, OF CHICAGO, ILLINOIS, A CORPORATION OF ILLINOIS.

CLAMP FOR BEDSTEAD ATTACHMENTS.

SPECIFICATION forming part of Letters Patent No. 759,560, dated May 10, 1904.

Application filed September 5, 1903. Serial No. 172,064. (No model.)

To all whom it may concern:

Be it known that I, GEORGE P. SHARP, a citizen of the United States, residing at Chicago, in the county of Cook and State of Illinois, have 5 invented a new and useful Improvement in Clamps for Bedstead Attachments, of which the following is a specification.

My invention relates to an improvement in the class of clamps used on the rails of metal 10 bedsteads for attaching thereto tables and other articles for use by the occupants of the beds and by surgeons and others in attending upon the occupants.

The end rails and the side rails of metal 15 bedsteads are commonly formed of angle-bars of L shape in cross-section and are disposed with the hollow sides facing upward for the end rails and with the hollow sides of the side rails facing downward, and it is 20 sometimes desired to apply a bed-table or other attachment to an end rail and sometimes to a side rail. Hitherto it has been the more common practice to provide a separate clamp for the sustaining-rod of the attachment for 25 connecting it with a side rail from that connecting it with an end rail, since owing to the different individual dispositions of the respective rails the same clamp is not applicable to each.

30 The object of my invention is to provide as a single article a clamp the peculiar construction of which shall adapt it to be applied for its purpose either to an end rail or to a side rail of the bedstead by adjusting the 35 clamp for either purpose reversely to its adjustment for the other.

Referring to the accompanying drawings, Figure 1 represents my improved clamp (by a perspective view) applied to a vertically-dis- 40 posed rod and attached to a bedstead side rail, of which a section is shown; and Fig. 2 shows by a similar view the application of my improved article to a bedstead end rail.

A is the metal clamp, comprising the arms 45 a and b at a right angle to each other, the arm a having its end bent to a right angle to form a jaw a', provided with a recess a² in its ex-

tremity, and the arm b having its end provided with a return-bend to form the jaw b', with an opening c in the arm b and set-screws 50 d and e working in threaded openings in the respective arms.

At B is represented, broken, the rod or stem for a table-top (not shown) to be clamped to a bed-rail C or D by introducing the rod 55 through the opening c in the clamp A and through the recess a² in its jaw a' and fastening the clamp in place.

To connect with a bedstead side rail C an attachment provided with a rod B depending 60 from it, the clamp-arm b is applied transversely over the upper wing of the rail to cause the jaw b' to engage the edge thereof when the clamp is tightened in place by properly turning the thumb-screw e, and the arm 65 a is thus brought to extend downward across the vertical wing of the rail when the rod B is introduced through the opening c and recess a², and the thumb-screw d is properly turned to tighten against the face of that wing 70 the rod B in any position to which it may be adjusted vertically. The coöperation of the screw e and the arm b thus effects the securing of the clamp in place, while that of the screw with the arm a effects the fastening in 75 adjusted position of the table or other attachment. To connect the attachment with a bed- 80 stead end rail D, from which a wire mattress E is shown to extend, the clamp-arm b is applied transversely under the lower wing of the rail to cause the jaw to engage its edge when the clamp is fastened in place by the screw e, thereby bringing the arm a across the vertical 85 rail-wing, with the recess a² and opening c in vertical alinement to admit through them the rod B to be fastened by the screw d.

The angular shape of the clamp should be such as to conform to the bedstead - rail, whether the latter be in the form of a right angle or other angle, so that my invention is 90 not intended to be limited to the exact shape of the clamp shown and described.

What I claim as new, and desire to secure by Letters Patent, is—

As a new article of manufacture, a reversibly-adjustable clamp for bedstead attachments of the character described, comprising, in combination, an arm *a* having a jaw *a'* on one end provided with a recess *a''*, an arm *b* extending at an angle from the other end of the arm *a*, provided with a jaw *b'* on its end and contain-

ing an opening *c* alining with the recess *a''* to receive a rod *B*, and set-screws working in the respective arms, substantially as described.

GEORGE P. SHARP.

In presence of—

SAML. G. PRINCE,
WALTER N. WINBERG.
